UNITED STATES PATENT OFFICE.

GEORGE J. NETH, OF DAYTON, OHIO, ASSIGNOR TO THE EGRY REGISTER COMPANY,
OF DAYTON, OHIO, A CORPORATION OF OHIO.

SELECTOR-HANDLE LOCK.

Application filed October 6, 1922. Serial No. 592,710.

To all whom it may concern:

Be it known that I, GEORGE J. NETH, a citizen of the United States, residing at Dayton, in the county of Montgomery and 5 State of Ohio, have invented certain new and useful Improvements in Selector-Handle Locks, of which the following is a specification, reference being had therein to the accompanying drawing.

10 My invention relates to registers having a plurality of drawers such as illustrated in my copending application No. 543,276, filed March 13, 1922.

It is the object of my invention to provide 15 an automatic stop for the selector handle which selects a drawer to be operated.

It is a further object to provide a selector indicator and selector handle in connection 20 with this automatic lock to lock the hand of the indicator at zero after each operation.

It is an additional object to provide means 25 of unlocking the locking mechanism so that the selector handle and indicator may move to the desired position.

Referring to the accompanying drawings:

Fig. 1 is a plan view of the selector mechanism in its locked position at zero;

30 Fig. 2 is a plan view of the selector mechanism in its unlocked position in position to select drawer one;

Fig. 3 is a section on line 3—3 of Fig. 1;

35 Fig. 4 is a section on the line 4—4 of Fig. 3, showing the details of the locking mechanism;

Fig. 5 is a front elevation of the unlocking plunger;

40 Fig. 6 is a side elevation of the unlocking plunger.

Referring to the details of the drawings, 1 is a selector plate provided with a slot 2 and a plurality of numerals 3 arranged on either side of a zero point 4. These numerals indicate the respective drawers so numbered in the cabinet, which has a plurality of drawers. It will be observed that these numerals are arranged on either side of the zero point 4. A pointer 5 travels adjacent to each one of these numerals and when located opposite one of them, that particular drawer is selected for operation, as explained in my copending application Serial No. 543,276, filed March 13, 1922.

55 The pointer 5 is mounted upon a selector

which consists of a handle 6 and a vertical member 7, which is carried by a lever 8. This lever 8 is connected through suitable mechanism, which forms no part of this invention, to the remainder of the mechanism for unlocking the respective drawers in the cabinet. Traveling in 7 vertically is an unlocking plunger 10 having a head 11 and a spring 12 to retain it in its inoperative position. This spring 12 is carried in 60 a cut-away portion 13 in 7, and serves to maintain the unlocking lug 14 carried by 10 in its inoperative position against a shoulder 15 in 7.

Beneath the plate 1 and spaced therefrom is a second plate 16. Between these plates there travels back and forth a locking plate 17 having a locking tooth 18 projecting into a cut-away portion 19 in the face of 7. 17 is constantly forced into engagement with 7 and into slot or opening 19 by a spring 20 which is mounted in a cut-away portion 21 in the table or cabinet top upon a pin 22. One end of the spring at 23 is engaged with the cabinet top and the other end is attached as at 24 to the locking member 17, thus constantly forcing it into engagement with the selector handle. The movement of 17 is limited by the pin 25 carried by 1 and by 16. This pin is located 70 in the slot 26 in 17.

It will be thus apparent that as the lever of the selector moves back and forth with its pointer, when it comes to the zero point it will be locked, and upon depressing the 90 plunger 10 through pressure being applied to the button 11, the plate 17 will be moved backwardly so that 18 will be pushed out of engagement with slot or opening 19 and the selector handle will be free to move 95 again to another position to select another drawer.

In the operation of the device, when the pointer is at zero and it is desired to open a particular drawer, the operator presses on 100 the button 11 to release the member 7 and moves the handle 6 until the pointer 5 is opposite the number of the drawer to be opened, whereby the member 7 and the rod 8 attached thereto are moved to release such drawer and mechanically retained in such position until the operator opens and closes such drawer, when the parts are automatically returned to zero position.

105 It will be understood that I have de- 110

scribed a preferred embodiment of my invention, that I do not desire to be confined to the details of the construction and comprehend within my claims various modifications of construction which may embody this invention.

Having fully described my invention, what I claim as new and desire to secure by Letters Patent, is:—

10. 1. In combination, a dial, a pointer, a selector carrying said pointer, which travels adjacent to the dial, a movable locking member carried by a cabinet top to engage locking means on the selector, and means carried by the selector to unlock the locking means by moving it out of locking position.
15. 2. In combination, a supporting cabinet top and cut-away portion therein for the movement therethrough of a selector handle, a dial mounted on said cabinet top, a pointer carried by said selector handle adjacent said dial, a locking plate moving transversely in said cabinet top adapted to engage with said handle and means carried by the handle for shifting said locking plate to unlock it, whereby when the handle is locked by the locking plate, said means may be utilized to unlock the handle.
20. 3. In combination, a selector handle, a plunger traveling vertically therein, yielding means to maintain said plunger in its inoperative position, an unlocking lug on said plunger, a stationary support, and a locking plate moving transversely in said stationary support and adapted to engage with said selector handle at a predetermined point, whereby when said handle is so locked the depression of the plunger will result in the unlocking of the handle therefrom.
25. 4. In combination a selector handle, a plunger traveling vertically therein, yield-

ing means to maintain said plunger in its inoperative position, an unlocking lug on said plunger, a locking plate adapted to engage with said selector handle at a predetermined point, whereby when said handle is so locked the depression of the plunger will result in the unlocking of the handle therefrom, and yielding means to maintain said locking member in engagement with the said handle when locked, and in the path thereof when unlocked, and means for limiting the movement of said locking member.

5. In combination, a supporting platform, a lever pivoted beneath said platform, a vertical standard on the end of said lever projecting through a slot in said platform above said platform, a numbered plate associated with said slot mounted on said platform, said plate having a variety of designations thereon and an inwardly directed finger on said standard, the free end of which is adjacent said designations, a handle mounted on the upper end of said standard oppositely disposed from said finger, a locking plate adapted to move inwardly and outwardly into said slot, means to guide said plate and limit its movement carried by said platform, yielding means carried by said platform to normally thrust said plate outwardly, said plate having a locking head, and means yieldingly supported in said vertical standard which when depressed will force said locking plate out of said slot, said vertical standard being adapted to move through said slot while said locking plate is stationary, save for its reciprocating movement.

In testimony whereof, I affix my signature.

GEORGE J. NETH.
